UNITED STATES PATENT OFFICE.

CHARLES H. GAFFNEY, OF GLOUCESTER, MASSACHUSETTS.

BRAKE-HANDLE.

SPECIFICATION forming part of Letters Patent No. 553,848, dated February 4, 1896.

Application filed June 5, 1895. Serial No. 551,730. (No model.)

To all whom it may concern:

Be it known that I, CHARLES H. GAFFNEY, a citizen of the United States, and a resident of Gloucester, in the county of Essex and State of Massachusetts, have invented new and useful Improvements in Brake-Handles, of which the following, taken in connection with the accompanying drawings, is a specification.

This invention relates to improvements in brake-handles for railway-cars; and it has for its object to enable the brakes to be released without revolving the handle-lever, thus preventing accidents to motor or brake men or passengers on the car-platform by the quick rotary motion of the usual brake-handles when the brake is released.

The invention is carried out as follows, reference being had to the accompanying drawings, wherein—

Figure 1 represents a top plan view of my improved brake-handle, showing in dotted lines the handle-crank swung into a horizontal position during the release of the brake. Fig. 2 represents a longitudinal section on the line 2 2 shown in Fig. 1. Fig. 3 represents a detail side elevation of the ratchet and pawl, showing the latter in its released position. Fig. 4 represents a detail sectional view on the line 4 4 showing the pawl in its normal locked position relative to the ratchet-wheel, and Fig. 5 represents a cross-section on the line 5 5 shown in Fig. 2.

Similar letters refer to similar parts wherever they occur on the different parts of the drawings.

A in Figs. 2 and 3 represents the vertical brake-shaft, as usual, to the upper end of which is secured the hub B, having preferably at or near its upper end a ratchet-wheel or tooth-wheel B', as shown in Figs. 2, 3 and 4.

The hub B is provided with an annular groove or recess B'', arranged on one side of the said ratchet-wheel, preferably on its under side, as shown in Figs. 2 and 3.

On the hub B is loosely pivoted a sleeve C, in which is journaled the pawl rod or arm D, having a pawl d at its inner end adapted to engage with the ratchet-wheel B', as shown in Figs. 2 and 4.

To the outer end of the arm D is secured a crank-handle E, which is normally held in

an upright position (shown in full lines in Figs. 1 and 2) by the influence of a spring F, secured in one end to the rod D, and in its other end to the sleeve C, as shown in Fig. 2. The said spring F also serves the purpose of holding the pawl d with a yielding pressure in engagement with the ratchet-wheel B', as shown in Fig. 2.

In practice I prefer to screw a screw-threaded bearing G into the end of the sleeve C, as shown in Figs. 1 and 2.

H is a pin or projection on the rod D, adapted to serve as a stop to limit the rocking motion of the rod D as the handle-crank E is swung from its normal vertical position to the horizontal position shown in dotted lines, Fig. 1.

g' are stop projections on the bearing G, 70 against which the pin H is brought to rest when the handle E is moved to its respective vertical and horizontal positions.

The operation is as follows: Normally the handle E is held upright by the spring F, in which position the pawl d is in engagement with the ratchet B', and when in such position the brake-handle may be actuated to set the brake in a manner similar to the usual ratchet brake-handles. If it is desired to release the brake, all that the operator has to do is to swing the handle E to a horizontal or nearly so position, when the pawl d will be brought into the annular groove B'' and out of engagement with the ratchet-wheel B', thus allowing the free turning of the shaft A during the release of the brake without rotation of the sleeve C, its rod D and handle E, for the purpose set forth.

Having thus fully described the nature, 90 construction, and operation of my invention, I wish to secure by Letters Patent and claim—

1. The herein-described brake-handle consisting of a brake-shaft A having a ratchet-wheel B' secured to it and an annular groove 95 B'' on one side of said ratchet-wheel combined with a sleeve C pivoted on said ratchet-wheel and a yielding pawl-rod engaging the latter and adapted to enter the annular groove B when the handle E is oscillated, substantially as and for the purpose set forth.

2. In a brake-handle in combination a ratchet-wheel on the brake-shaft, a sleeve pivoted thereon and having a longitudinally

yielding and oscillating pawl-arm provided with a handle at its outer end and normally held in working engagement, by means of a spring with said ratchet-wheel and adapted to be released from the latter by the turning of the said pawl arm and handle, substantially as and for the purpose set forth.

5 In testimony whereof I have signed my

name to this specification, in the presence of two subscribing witnesses, on this 28th day 10 of May, A. D. 1895.

CHARLES H. GAFFNEY.

Witnesses:

ALBAN ANDRÉN,
LAÜRITZ N. MÖLLER.
